NONREFILLABLE BOTTLE

Joseph J. Crossman, New York, N. Y.

Application January 23, 1935, Serial No. 3,135

1 Claim. (Cl. 215—22)

This invention relates to non-refillable bottles and has for its principal object the provision of a device adapted to be attached to the neck of a bottle by which to prevent the refilling of the bottle after the contents thereof have been decanted.

Devices of the character indicated as heretofore used have presented certain difficulties and objections in operation, such as the failure of the device to provide a secure closure for the bottle in its horizontal position. Such devices also cause the liquid being poured out of the bottle to be discharged at a very slow and intermittent rate.

In view of the above, a further object of my invention is to provide a non-refillable bottle from which the contents may be poured in an even full stream without interruption or gurgling and also to provide in such a device the novel arrangement and cooperation of the elements by which the bottle will remain sealed in all positions from the upright to the horizontal.

The invention will be fully and comprehensively understood from a consideration of the following detailed description when read in connection with the accompanying drawing which forms part of the application, with the understanding, however, that the improvement is capable of extended application and is not confined to the exact showing of the drawing nor to the precise construction described and, therefore, such changes and modifications may be made therein as do not affect the spirit of the invention nor exceed the scope thereof as expressed in the appended claim.

In the drawing:

Fig. 1 is a central vertical sectional view of my device attached to a bottle.

Fig. 2 is a view similar to Fig. 1 with the axis of the bottle horizontal.

Fig. 3 is a view similar to Fig. 1 but with the bottle in pouring position; and

Fig. 4 is a transverse sectional view taken on line 4—4 of Fig. 1.

Referring now to the drawing for a more detailed description thereof, the numeral 5 indicates generally the housing of my device which comprises an upper cylindrical chamber 6, the top end 7 of which is closed. The cylindrical wall 50 of the chamber 6 in its preferred form is enlarged at its middle to expedite the flow of liquid thru the device. From the lower end of the chamber 6 depends a tapered cylindrical member 8 adapted to fit snugly on the tapered portion of a bottle neck and is secured thereon in suitable man-

ner as by rolling or flanging in the free edge of the cylinder 8.

A valve cage 9 of hollow cylindrical form is inserted into the neck opening of the bottle so that its radial flange 10 rests against the edge of the bottle neck, a suitable gasket 11 being provided to seal the joint between these members. A flange 12 extending inwardly from the housing 5 is disposed to engage the flange 10 so as to hold the valve cage 9 securely in place after the edge of the cylinder 8 has been flanged in. Radial arms 13 project inwardly from the bottom of the valve cage 9 to support a centrally disposed valve bearing 14. A valve 15 of the poppet type has its edges bevelled to seat against the upper edge of the valve cage 9 and has its stem 16 slidably supported in the bearing 14. The upper surface of the poppet valve 15 is provided with a shallow conical recess 17 so that in the vertical position of the bottle the weighted ball 18 takes a central position on the valve.

Integral with the upper end 7 of the housing and depending interiorly therefrom is formed a cup-like structure 19, the interior surface of which diverges downwardly terminating at the circular edge 20 and concentric with the axis of the valve 15. The size of the cup 19 and also the disposition of its edge 20 with relation to the valve 15 is an important feature of my device. Reference to the position of the parts in the horizontal position of the bottle, as illustrated in Fig. 2, will make this arrangement more apparent. The edge 20 must be spaced from the top surface of the valve 15 a lesser distance than the diameter of the ball 18 so that in the horizontal position of the device the ball 18 will lodge between the lowermost portion of the edge 20 and the top surface of the valve 15 to hold the valve closed by wedge-like action.

A pouring spout 21 is constructed in the cylindrical wall of the chamber 6 to extend radially therefrom and is disposed at such an angle as to facilitate pouring from the bottle. The spout 21 extends inwardly to terminate at the tapered wall of the cup 19. Diametrically opposed apertures 22 are cut in the inwardly extending portion of the spout 21 by which to connect the latter with the interior of the chamber 6 and particularly the annular recess around the cup 19. The formation of the spout 21, particularly the arrangement of the apertures 22 therein, is provided to prevent the insertion of a wire into the nozzle by which to hold the valve 15 open and thus permit the refilling of the bottle.

In pouring from the bottle the latter is of course

tilted at an appreciable angle, as illustrated in Fig. 3. In this position the weighted ball 18 will dislodge itself from between the edge 20 and the valve 15 and thus roll into the cup 19. The valve 15 slides in its bearing 14 to full open position and thus permits the free flowing of the liquid from the bottle. In order to obviate any interruption of the discharge of the liquid thru the nozzle 21, such as that caused by the inrush of air to displace the liquid, a vent hole 23 is cut in the upper cylindrical wall of the housing 5 at a point diametrically opposite the spout 21. Thru the vent 23 air is admitted to the interior of the bottle, thus facilitating the free discharge of the liquid from the spout 21.

What is claimed as new is:

An anti-refilling structure for bottles comprising a hollow casing, a valve in said casing adapted to normally close the mouth of a bottle and a free weight for holding said valve in closing position until said structure is tilted below horizontal position, a flared cup depending within said casing and adapted to receive said free weight when the bottle is in pouring position, an annular chamber around said cup, said casing having a vent adjacent said annular chamber to admit air into same and a pouring spout in communication with said chamber and opposed to said vent aperture. 5
